W. F. WOLF
LOOSE LEAF BINDER
Filed Feb. 24, 1928

WALTER F. WOLF
INVENTOR
BY *Victor J. Evans*
ATTORNEY

UNITED STATES PATENT OFFICE

WALTER F. WOLF, OF NEW YORK, N. Y.

LOOSE-LEAF BINDER

Application filed February 24, 1928. Serial No. 256,727.

This invention relates to loose leaf binders and is an improvement over the binder shown and described in my pending application Serial No. 239,537, filed December 12, 1927.

5 The primary object of the invention resides in a binder in which the binding posts thereof may be laterally adjusted to accommodate loose leaves irrespective of the spaced relation of the usual openings provided therein 10 and through which the posts pass when the loose leaves are inserted into the binder.

Another object is the provision of a loose-leaf binder in which the back cover is hingedly connected to a flat tubular base member 15 which slidably receives post carriers which may be adjusted to various spaced relations by rotatable screws which are respectively key controlled from the opposite ends of base member, while the front cover section is 20 hinged to a flat tubular base member in which carriers are also slidably mounted for supporting the binder locking devices which are engageable with the posts rising from said post carriers and which may be manually adjusted 25 for alignment with the post carriers to engage the respective posts.

A further object is to provide a loose-leaf binder which includes all the features provided in the construction of binder shown 30 and described in the above mentioned application, together with a means for laterally adjusting the binding posts and respective locking devices relative to each other.

With these and other objects in view, the 35 invention resides in certain novel construction and combination and arrangement of parts, the essential features of which are hereinafter fully described, are particularly pointed out in the appended claims, and are 40 illustrated in the accompanying drawing, in which:—

Figure 1 is a vertical transverse sectional view through my improved binder.

45 Figure 2 is an enlarged fragmentary vertical transverse sectional view through the back tubular base member.

Figure 3 is an enlarged vertical transverse sectional view on the line 3—3 of Figure 1.

Figure 4 is a detail perspective view of one of the screw bearing blocks.

Figure 5 is a detail horizontal sectional view on the line 5—5 of Figure 2.

Referring to the drawings by reference 55 characters, the numeral 10 designates my improved loose-leaf binder in its entirety which includes a back section 11 and a front section 12 between which the loose-leaves to be bound are placed.

60 The back section 11 comprises a flat tubular base strip 13 of a length equal to the width of the binder and to which a rigid back cover 14 is hingedly connected as at 15. The ends of the base member are closed by solid caps or 65 plugs 16 while riveted within the member midway between its ends is a bearing block 17 having a groove 18 therein and a notch 19 extending inwardly from one of the side edges to provide a bifurcation. Journalled in the bearing block 17 are the inner reduced ends of 70 a pair of rotatable screw shafts 20, 20, which reduced ends seat in the groove 18 with their extreme ends terminating in the bifurcation or notch 19. Washers 21 are mounted on the 75 reduced ends and abut the inner walls of the notch and the outer sides of the bearing blocks while the inner ends of the screw shafts are upset to provide heads which serve to swivelly connect the screw shafts with the bearing 80 blocks. The outer ends of the screw shafts are journalled for rotation in the end caps 16 and have their outer squared ends 22 terminating within recesses 23 provided therein.

85 The top and bottom walls of the tubular base member 13 are provided with aligned elongated slots 24 while slidably mounted within the tubular member for movement with respect to each other are post carriers 25 having threaded bores 26 for co-action with 90 the threaded screw shafts 20. From the description thus far, it will be understood that upon rotation of either of the screw shafts by applying a key 27 to the squared end thereof, a turning movement may be manually imparted to the screw shaft which will impart a 95 sliding movement to its related carrier 25. By providing two separate screw shafts, the carriers may be independently actuated.

The carriers 25 support binding posts 28 100

each of which includes a base socket member 29 having a flange 30 which fits between the walls of the slot 24 and upon the top of the carrier 25. The socket member is provided 5 with an internally threaded bore which receives a threaded stud 31 which passes upward through a threaded bore in the carrier. The stud is provided with a square head 32 disposed in a recess 33 in the underside of the carrier and which is of a size to receive the same key 27 used for turning the screws 20. The key is inserted through the slot 24 in the bottom wall of the tubular member when fitting it to either of the studs. The binding 10 post is built up from the socket member 29 and embodies a plurality of threaded sections 34 which are fully explained in my co-pending application above mentioned. It will be seen that each carrier 15 25 supports a post which is movable therewith and capable of adjustment to various lateral positions with respect to each other to accommodate the spaced openings 35 in the loose-leaves 36, irrespective of their spaced relation. 20 25 The screws are turned to move the posts to the desired position and the loose leaves 36 placed thereon in the usual manner.

The front section 12 above referred to includes a tubular base member 37 similar to the 30 tubular base member 13, and to which the front rigid cover 38 is hingedly connected as at 39. The base member 37 is closed at its ends by caps 40 while a partition 41 is riveted 35 within the member midway between its ends to strengthen the walls thereof. The opposed flat walls of the base member 37 are provided with aligned elongated slots 42 to allow for the passage of the binding posts 28.

Slidably mounted within the tubular member 40 on opposite sides of the partition 41 are blocks 43 which support binder locking devices 44. Both of the blocks 43 and locking devices are identical so that a description of one will suffice for the other. The locking devices are fully explained in my co-pending application and include a hollow casing 45 from which a tubular sleeve 46 extends, the same being externally screw threaded for threading engagement with a threaded bore 47 in the 45 block 43. The top of the casing is closed by a cover plate 48 having an opening therein for the passage of the post and from which a tongue 49 extends. A slot 50 is provided in the side wall of the casing 45 while a locking disk 51 is loosely contained within the casing and has a finger 52 extending through the slot for movement over the bottom wall thereof and which bottom wall is beveled inwardly 55 at one end as at 53. The disk 51 has a central opening 54 therein for the passage of the post to which the lock is applied. The locking disk is held in an unlocked position when the finger 52 is moved to a position in alignment 60 with the tongue 49, as the said finger rests

upon the flat bottom wall of the slot and is held in a horizontal position by the finger engaging beneath the tongue. The post is free to slide therethrough but when locking the device, the manipulating finger 52 is pushed 70 from beneath the tongue to the beveled end of the slot which allows the disk to drop to an angular position for jamming engagement with the post as shown at the left of Figure 1 of the drawings. After the locking devices have been screwed to their respective 75 sliding blocks, they form an integral part of the front cover section and need not be disturbed when removing the front cover section from the posts, as the actuation of the lock disk need only be touched. To adjust the locking devices, the operator merely slides them to a position in alignment with the posts whereupon the front section may be placed into position.

From the foregoing description, it will be seen that I have provided a loose-leaf binder in which the binding posts may be adjusted relative to each other to suit the leaves to be held. It will be appreciated that loose-leaves 80 of different sizes have the post openings at different spaced intervals which requires separate binders therefor, but with my improved binder, it is possible to insert sheets in which the post holes may vary as the posts 85 may be laterally adjusted to suit the requirements.

While I have described what I deem to be the most desirable embodiment of my invention, it is obvious that many of the details may 90 be varied without in any way departing from the spirit of my invention, and I therefore do not limit myself to the exact details of construction herein set forth nor to anything less than the whole of my invention limited only 95 by the appended claims.

What is claimed as new is:—

1. In a loose-leaf binder, a back cover section including a tubular base member having an elongated slot therein aligned screw 110 shafts journaled in said tubular base member carriers threaded to the respective shafts, binding posts rising from said carriers, and studs threaded to said carriers and into said binding posts and accessible for removal through said elongated slot.

2. In a loose-leaf binder, a flat tubular member having an elongated slot therein, carriers slidably mounted in said tubular member, threaded studs passing through said carriers and accessible for removal through said slot, and binding posts respectively threaded to said studs.

3. In a loose-leaf binder, a flat tubular base member closed at opposite ends, a bearing member mounted within said base member midway between the ends thereof, axially aligned screw shafts having their inner ends journaled in said bearing member and their 125 outer ends accessible for removal through said base member.

outer ends journaled in the closed ends of said base member carriers threaded to said screw shafts, and binding posts mounted on said carriers and extending therefrom.

⁵ In testimony whereof I have affixed my signature.

WALTER F. WOLF.
